UNITED STATES PATENT OFFICE.

HARRY L. BEACH, OF COSHOCOTON, OHIO.

DESIGN FOR A BOTTLE-OPENER.

41,807.

Specification for Design.

Patented Sept. 26, 1911.

Application filed October 29, 1910. Serial No. 589,832. Term of patent 7 years.

To all whom it may concern:

Be it known that I, HARRY L. BEACH, a citizen of the United States, residing at Coshocton, in the county of Coshocton and State of Ohio, have invented a new, original, and ornamental Design for Bottle-Openers, of which the following is a specification.

Reference is had to the accompanying drawing, in which:—

Figure 1 is a perspective view of a bottle opener, showing my new design. Fig. 2 is a plan view of the same. Fig. 3 is a reverse plan view.

As shown in the drawing, the bottle opener has a longitudinal groove or depression, extending along the handle 1 at 2 and around the head 3 at 4. The groove or depression 2 of the handle extends from one side edge to the other. The head 3 has a transversely elongated opening 5, and the groove 4, which is narrower than the groove 2, extends around the head and from the

inner edge of the head at the opening 5 to the outer edge of the head. The handle and head portions of the bottle opener are curved transversely. The upper face of the opener is concave and the lower face 6 is convex. The upper face is ornamented by marginal scroll work 7, extending around the side portions of the handle and the sides of the head. The head is arched at 8 at the inner transverse edge of the opening 5, and the arched portion tapers toward the handles.

I claim:—

The ornamental design for a bottle opener, as shown and described.

In testimony, that I claim the foregoing as my own, I have hereto affixed my signature in the presence of two witnesses.

HARRY L. BEACH.

Witnesses:

W. G. HOOTMAN,
MARGARET QUINLAN.
